UNITED STATES PATENT OFFICE.

WILLIAM F. SWEZEY, OF DAYTON, OHIO, ASSIGNOR, BY MESNE ASSIGNMENTS, TO
FRIGIDAIRE CORPORATION, A CORPORATION OF DELAWARE.

REFRIGERATING APPARATUS.

Application filed June 30, 1926. Serial No. 119,715.

This invention relates to refrigerating apparatus, and particularly to the construction of cabinets for commercial use, which are commonly known as "ice-cream cabinets." The cabinet construction in present use is composed, generally, of an insulated cabinet containing a brine tank in which is submerged a receptacle, or sleeve, of various shapes, adapted to contain ice cream or any other substance which it is desired to cool. These cabinets are provided with a top having an opening to permit access to the aforementioned sleeve, and a cover is provided to close this opening. It is the practice to space the upper edge of the cabinet top a considerable distance above the top of the brine tank and to support the cover by a gasket, or other similar means, which is carried by the cover and rests on the upper edge of the top of the cabinet. Such a construction is shown in the copending application of Jesse G. King, Serial No. 86,586, filed February 6, 1926. This construction, however, provides a seal between the outside air and the interior of the cabinet, at only one place, namely, where the cover is supported by the cabinet top and, consequently, there is a large, free air space left surrounding the cover and the upper part of the food container. This space permits a free circulation of air about the upper part of the food container and as this air, due to leakage past the cover through the single seal, is warmer than the cooling means surrounding the lower part of the food container, it has a tendency to soften substances in the food container, which is, in itself, a very objectionable feature of the present type of cabinet construction.

It is an object of this invention to effectually seal the food compartment against the entrance of warm air thereto, and to prevent any interchange of temperature between the inside and the outside of the cabinet.

It is a further object to provide the food container with a closed metallic casing, which is adapted to maintain a uniform temperature throughout the entire container and to effectually seal the same against the influence of external temperatures. The desired results are accomplished in the following man-

ner: The sleeve which receives the food container, and which is almost entirely immersed in the brine tank, is allowed to project a short distance above the top of the tank. The cover for the opening in the cabinet top is provided with a recess and in this recess is placed a plate of metal, or other heat-conducting material. The lower side of the outer periphery of the cover is provided with a suitable sealing means, such as a gasket of rubber, fabric, or other yieldable material; and the outer periphery of the upper side is, likewise, provided with a similar seal. The recess provided in the lower side of the cover is made of slightly greater diameter than that of the upwardly-projecting part of the sleeve, so that, when the lid is set in place, the metallic plate provided in the recess will contact with the upwardly-projecting portion of the sleeve. The sealing means carried by the lower side of the cover will then rest on the upper side of the brine tank surrounding the upper end of the sleeve and the seal carried by the upper side of the cover will rest on top of the cabinet. By this construction the sleeve and the food container carried thereby are both sealed and insulated against the influence of temperatures external to the cabinet, while at the same time the heat-conducting plate carried in the recess provides an effectual means for transferring any heat from the top of the sleeve surrounding the upper part of the food container to the remaining walls of the sleeve where it is absorbed by the cold brine.

Referring to the drawings, where there is shown a specific embodiment of a means by which the above-described result may be accomplished, Fig. 1 is a vertical section through the refrigerating cabinet, including the cover; and

Fig. 2 is a view on an enlarged scale, showing details of the cover construction.

10 designates, generally, an insulated refrigerating cabinet which contains suitable cooling means, such as a brine tank 11. 95 Within the brine tank is inserted a plurality of heat-conducting sleeves, one of which is shown at 12. Each sleeve is provided with a portion 13 which projects above the top 14 of the brine tank. The cabinet has a top 100

15 provided with openings 16 which give access to the sleeves 12. Inside the opening there is provided an insulating sleeve 17 which extends from the top 14 of the brine tank to the upper edge of the cabinet top 15. A spring ring 18 serves to hold the insulating sleeve in place and at the same time provides a support for a purpose to be described. The details of the cabinet construction are 10 fully described in the copending application of Jesse G. King, mentioned above.

The sleeve 12 may be provided at its upper end with an additional, shorter sleeve 19 which extends upwardly and is lapped over 15 the upwardly-projecting portion 13 of sleeve 12. The second sleeve 19 is provided to protect the upper end of the first sleeve against injury by the insertion and removal of the food container, which is shown at 20. If 20 this sleeve should be damaged, it can be readily removed and replaced.

A cover 21 for the opening 16 may be made of any desired material, but is here shown as composed of an annulus 22 provided at its 25 lower side with a recess 23. In this recess fits a cup-shaped plate 24 which may be of metal or other heat-conducting material. The top of the cover is provided with a metal plate 25 and the space between the plates is 30 filled with a suitable insulating means, such as corkboard 26. The plates are spaced, one from the other, at the middle portions thereof by a suitable spacing block 27, through which passes a screw or bolt 28 which extends 35 into a handle 29. The upper side of the annulus 22 is provided at its periphery with a groove 30 which receives a suitable sealing gasket 31. This gasket projects beyond the periphery of the annulus and is adapted to 40 rest on the sealing ring 18 when the cover is in position. The gasket 31 is held in place by the spring action of the top metal plate 25.

The lower surface of the annulus 22 is provided at its periphery with a sealing gasket 45 32 which may be fastened thereto by suitable means, such as screws 33. This sealing gasket is adapted to rest on the top 14 of the brine tank cover when inserted in the opening 16.

It will thus be seen that when the cover 21 50 is placed in position to close the opening 16, the sealing gasket 32 will rest on the brine tank around the upwardly-projecting portion 13 of the sleeve 12, the metallic plate 24, carried in the recess in the cover will make 55 contact with the aforementioned sleeve and the seal 31 will rest on the spring-ring 18. Thereby the opening 16 is sealed in two places, the upper end of the sleeve 12 is effectively insulated against outside temperature 60 conditions, while at the same time the conducting plate 24 and the sleeve 12 form a closed metallic chamber which will have a uniform temperature throughout its entire surface.

65 While the form of embodiment of the in-

vention as herein disclosed, constitutes a preferred form, it is to be understood that other forms might be adopted, all coming within the scope of the claims which follow.

What is claimed is as follows:

1. An ice cream cabinet comprising a tank for refrigerating liquid, an ice cream compartment in said tank including a metal sleeve adapted to extend into and above said liquid, an insulated top for said cabinet having an opening in alignment with said sleeve, a unitary cover for said ice cream compartment and for said opening, said cover including a metal plate adapted to fit on the side wall of said sleeve and to extend across the sleeve, said cover also including an insulated portion for sealing said opening in said top and means for removing said cover as a unit from its normal position in said cabinet.

2. A cabinet comprising a tank for refrigerating liquid, a compartment in said tank including a metal sleeve adapted to extend into and above said liquid, a top for said cabinet having an opening in alignment with said sleeve, a cover for said compartment and for said opening, said cover including a metal plate on the under side thereof having metallic thermal contact with the sleeve, said cover also including an insulated portion for sealing said opening in said top.

3. An ice cream cabinet comprising a refrigerated metallic sleeve forming an ice cream compartment, an insulated top for said cabinet having an opening in alignment with said sleeve, a unitary cover for said ice cream compartment and for said opening, said cover including a metal plate adapted to fit on the side wall of said sleeve and to extend across the sleeve, said cover also including an insulated portion for sealing said opening in said top, and means for removing said cover as a unit from its normal position in said cabinet.

4. An ice cream cabinet comprising a tank for refrigerating liquid, an ice cream compartment in said tank including a metal sleeve adapted to extend into and above said liquid, an insulated top for said cabinet having an opening in alignment with said sleeve, a tank sub-cover extending radially inward from the periphery of said opening to said sleeve, a unitary cover for said ice cream compartment and for said opening, said cover including a metal plate adapted to fit on the side wall of said sleeve and to extend across the sleeve, said cover also including an insulated portion for sealing said opening in said top, and including a seal adapted to fit around said sleeve substantially to said sub-cover to insulate the top of said sleeve, and means for removing said cover as a unit from its normal position in said cabinet.

5. A cabinet comprising a tank for refrigerating liquid, a compartment in said tank including a metal sleeve adapted to extend into and above said liquid, a top for said cabinet

having an opening in alignment with said sleeve, a cover for said compartment and for said opening, adapted to seal the air in said sleeve and including a metal plate having contact with the air in said sleeve and refrigerated by metallic thermal connection with the refrigerating liquid adjacent to said

sleeve, said cover also including an insulated portion joined to said metallic plate for sealing said opening in said top.

10

In testimony whereof I hereto affix my signature.

WILLIAM F. SWEZEY.
